UNITED STATES PATENT OFFICE.

CHARLES S. BRITTON, OF CLEVELAND, OHIO.

GOLF-PRACTISING DEVICE.

1,164,985.

Specification of Letters Patent. Patented Dec. 21, 1915.

Application filed May 23, 1914. Serial No. 840,625.

To all whom it may concern:

Be it known that I, CHARLES S. BRITTON, a citizen of the United States, residing at Cleveland, in the county of Cuyahoga and State of Ohio, have invented a new and useful Improvement in Golf-Practising Devices, of which the following is a specification, the principle of the invention being herein explained and the best mode in which 5 I have contemplated applying that principle, so as to distinguish it from other inventions.

My invention has general reference to a golf practising device and more particularly 15 to one in which a golf ball or its equivalent in size is movably attached and capable of assuming approximately the usual or average position of rest preparatory to being struck.

20 The primary object is to make possible a repeated driving without requiring either a recovery of the ball or a removal of the player to a different location.

A further object consists in the provision 25 of suitable means for indicating the efficacy of any or each successive stroke.

The inventive conception is associated with means which are hereinafter explained and variously combined in the claims.

30 While the annexed drawing and particular description thereof, jointly set forth in detail preferred and modified forms embodying my invention, it should be understood that the means only exemplify some of many 35 diversified mechanical forms with which the principle of my invention may be justly applied.

Figure I is a part section part elevation of one preferred embodiment of my invention. Fig. II is a section on line II—II of Fig. I looking in the direction of the arrows. Fig. III is a plan of one detail of Fig. I. Fig. IV is a modification in respect to one detail.

45 Adverting to the several views in numerical sequence and considering first Figs. I to III inclusive, it will be seen that the invention is shown mounted upon an elevated platform A embodying uprights a' and a horizontal flooring a² which latter is provided intermediately of its ends with an elongated slot a³ having in this instance spherical end surfaces a⁴. The flooring a² is furthermore provided a given distance 50 to one side with an opening a⁵ and mounted adjacent the latter is a pedestal a⁶. The purpose of the opening a⁵ and pedestal a⁶

will hereinafter become apparent. The flooring a² is also provided with a countersunk opening a⁷ on that side of the slot a³ 60 which is opposite to the opening a⁵.

Suspended from the flooring a² by means of screws b', on each side of the slot a³ is a bracket B. The brackets B are formed below as an annular flanged rim b², which 65 incloses an outer race b³ and an inner race b⁴ provided with a horizontal bore b⁵. Operatively held for movement between the inner and outer races are a plurality of balls b⁶. A shaft C is fixedly mounted for rotation in the alined horizontal bores b⁵. The shaft has one extremity c' projecting in the direction of the opening a⁵, while its opposite end is formed with a cranked arm e² 70 having a horizontal continuation e³ normally directly underneath the opening a⁷. The purpose in so locating it will be later described.

Fixedly mounted upon the shaft C between the bores b⁵ is a ball supporting structure D. Such mounting is effected through the agency of a hub d'. The structure D involves an arm d² adapted to extend outwardly through the slot a³, and in a direction diametrically opposite to that of the 85 arm e². The outer extremity of the arm d² is fashioned as a spherical surfaced cup d³ designed to conform to the size of any officially adopted golf ball d⁴. The center of the cup d³ should be, when the arm d² is in 90 its upright position, a distance above the upper surface of the flooring a² corresponding to an average elevation of a golf ball upon its tee. Such ball may be further held in place by a spring finger d⁵ adapted to engage the under surface of that side which is exposed, as clearly seen in Fig. II.

An indicating device E adapted preferably to register in yards, and as illustrated in Fig. III according to a scale from zero 100 to three hundred, is pivotally mounted upon the pedestal a⁶. The device E comprises an indicating finger e' adapted automatically to return to zero, and a recording finger e² adapted to remain in the position to which 105 it was carried by the movement of the indicating finger e'. Both fingers are operatively connected with the extremity e' through the agency of a flexible shaft e³. Since nothing is claimed for the interior 110 mechanism of the indicating device, it will be presumed to have been properly calibrated such that the revolutions of the ball d⁴ are translated upon its dial in yards.

For convenience it is desirable to have the golf ball normally maintained in its uppermost position preparatory to the delivery of any particular practice stroke and it is for this purpose that a spring controlling mechanism F is supplied. This mechanism involves a spring seat collar f' held in any suitable manner upon the extremity c^3 of the shaft, and another spring seat f^2 held in vertical alinement therewith by a set screw f^3 . A compression balance spring f^4 operatively connects the collar f' and seat f^2 whereby the extremity c^3 is normally held in its lowermost position and hence the arm d^2 in its upright position.

As should now be readily understood, a player may stand a suitable distance beyond the opening a^7 and facing the indicating device E and thus be in a position to address the ball and perfect himself by a successive driving of the same in the direction indicated by the arrow in Fig. II or toward the line of vision in Fig. I. As earlier suggested, the number of revolutions imparted by the blow upon the ball d^4 may be accurately translated into yards by the recording finger e^2 and the fulfilment of the purposes of my invention thereby attained.

The modification outlined in Fig. IV resides solely in making the ball there indicated as d^6 integral with the extremity of the arm d^2 .

My invention being thus described with sufficient thoroughness, what I desire to secure by Letters Patent and therefore claim specifically, is:

1. A golf practising device comprising a support, a crank arm revolvably mounted thereon, the extremity of said arm being provided with a gripping device and a golf ball carried by the latter.

2. A golf practising device comprising a structure adapted for insertion into the earth so as to form a hollow compartment in conjunction therewith, and a member mounted for movement within such receptacle and provided upon its outer end with a ball, said ball being adapted to describe an arcuate path above the surface of said structure, and a balance spring operatively associated with said member and adapted to normally maintain such outer end uppermost.

3. A golf practising device comprising a hollow support, ball bearings therein, an arm rotatably mounted upon said bearings, the extremity of said arm having a spherical surface and adapted to project a given distance beyond the top of said support, a balance spring for normally holding such surface above said support, and means disposed above the latter for adjusting said spring.

4. A golf practising device comprising a hollow support set below the ground surface and provided above with a recess, a shaft rotatably mounted below said recess, and provided with a bent extension, an arm secured to said shaft and having its free end carrying a spherical surface, such spherical surface being adapted to project a given distance above said ground surface, and yielding means for normally maintaining said extension in its lowermost position.

5. A golf practising device comprising a hollow support, a shaft rotatably mounted in said support and having a zig-zag portion projected in a given direction, an arm projected from said shaft in the opposite direction and having its free end supporting a ball, said ball being adapted to project a slight distance above the ground, a spring applied to said zig-zag portion to normally maintain the ball in such position, and a device flexibly connected with said shaft for measuring the kinetic energy of any movement imparted thereto.

6. A golf practising device comprising a support, a member movably carried thereby having a cup-shaped extremity adapted to embrace a golf ball, and a finger adapted to coöperate with such extremity to hold the ball in place.

7. A golf practising device comprising a support, a member movably mounted thereon, the extremity of said member being provided with a concave surface facing rearwardly with reference to the intended direction of movement to be imparted to said member, and a golf ball carried in said concavity.

8. A golf practising device comprising a support provided with a pair of substantially horizontal bearings, a shaft rotatably mounted therein and having one end projecting beyond one of said bearings, such projecting end being twice bent in relatively transverse directions, a golf ball holder revolvably carried by said shaft, and means to coöperate with said bent end whereby to hold it in a given position of rest.

9. A golf practising device comprising a support, a shaft rotatably mounted thereon, a rigid member fixedly secured to said shaft, a spherical surface at the extremity of said member, means coacting with such surface to hold a golf ball, and an indicating device flexibly connected to said shaft for translating the revolutions of said ball into yards.

Signed by me, this 19th day of May, 1914.
CHARLES S. BRITTON.
